CONSTRUCTION OF CAMS

Frank Bernard Halford, Edgware, John Longmuir Penman Brodie, London, and Robert Miller, Edgware, England, assignors to The De Havilland Aircraft Company Limited, Edgware, Middlesex, England, a company of Great Britain

Application August 3, 1943, Serial No. 497,241
In Great Britain October 6, 1942

2 Claims. (Cl. 29—148)

This invention relates to the construction of cams and comprises a method which is more particularly adapted for use in the construction of a master cam from which form cams can be produced. Such form cams may be employed for example in the manufacture of pieces, as for instance turbine blades, which are shaped by grinding according to the method and with the apparatus which forms the subject of the present inventors' copending application for United States of America Letters Patent Serial No. 492,740.

In the method of construction according to this invention the master cam is built up of a suitable number of separate sections connected by dowels and all keyed on a mandrel, each section which is constituted by a circular or other disc blank of suitable initial thickness having this thickness reduced by cutting away the metal on one face so as to leave a raised part the peripheral contour of which has the shape which that part of the cam is to have, all these sections being next assembled on a mandrel and the excess metal removed down to the shaped edges of the raised parts lying between adjacent sections, after which the sections are separated and the raised part on the one face of each is removed leaving both faces flat and parallel, the sections being next and finally assembled on the mandrel and the surface of the whole cam as thus built up finished off. This finishing as also the removal of the excess metal when the blanks are first assembled may be effected by suitable means for example either by grinding, turning or by hand work. In the shaping of the raised part on the one face of each section and for the removal of the metal necessary to effect this shaping there may be used an engraving machine or a machine of like type and this is employed in association with a pantograph copying apparatus. The necessary contour is thus taken and reduced from hand-made templates which have been made several times the full size of the cam. In the finished process when the sections have been finely assembled there will be removed any slight steps over the surface of the whole cam which may occur where the faces of the sections abut and as a result of the removal of the raised metal from the face of each section.

By this process a single lobe master cam can be made, but it is possible in the same way to form a cam having two or even more lobes as may be required. Where, however, it is desired to produce say a number of such master or form cams, it is preferable to make first a single lobe master cam as described above and then with the

aid of this to shape each form cam first as to one of its lobes and then by relative rotation of the master cam and the form cam to shape the second lobe of the latter.

5 By way of example the accompanying drawing illustrates the improved method of constructing a cam and in particular a master cam which is more especially intended for use in the shaping of turbine blades. In this drawing:

10 Figure 1 shows in perspective one of the discs or blanks from which the complete cam is built up this disc having been subjected to the first stage in the process.

15 Figure 2 is a side elevation of the series of discs as first assembled after each of them has been treated as shown in Figure 1.

20 Figure 3 is a side elevation of the assembled discs after they have been next treated to remove the amount of metal necessary to bring the whole down to approximately the correct form for the cam.

25 Figure 4 is again a side elevation of the assembled disc sections, but after each of them has had its thickness reduced by the removal of the superfluous metal from the one face.

Figure 5 is an end view of the finished cam.

Figures 6, 7, 8 and 9 are side elevations of parts of two adjacent discs illustrating on an enlarged or exaggerated scale the several stages in the process.

30 Figure 10 is a side elevation of a single lobe master cam as it may be arranged for the formation of a two-lobed form cam.

Figure 11 is an end view of such a two-lobed cam.

35 In the first place there are taken a suitable number of similar circular discs of such thickness as may be desirable. In some cases all the discs may have the same thickness, but in other cases it may be convenient for some of them to be thicker than others and in the same way the diameters of all the discs may be the same or may differ. Each such disc A as seen in Figure 1 has through it a hole B for the mandrel on which

40 45 the assembled discs are mounted, and two holes C for dowels, and in the hole B is a keyway B' to permit of fixing the disc section on the mandrel. Each disc or blank has initially a thickness which is slightly greater than the section of the cam constituted by the disc will have finally so that when these discs are first assembled on the mandrel D as seen in Figure 2 the overall length of the body formed by them will exceed the length which the finished cam is to have. This can be seen by comparing the length of the built-

up body as shown in Figure 2 with the finished cam as shown in Figure 4. The excess thickness of each blank may be of the order of .02 inch, but may be determined as found desirable.

Each individual disc A is subjected to a process by which there is removed from its one face a layer of metal of uniform thickness over such marginal or other part of the face as will result in there remaining a part A¹ which projects from the flat face part A² around that part A¹. This can be clearly seen in Figure 1 where it may also be seen that the projecting part has a flat face which is actually a part of the original side face of the blank while the contour of the edge A³ of the part A¹ is that which is to be given to the part of the cam which will ultimately be constituted by this section. The extent to which the shaped part A¹ projects from the surface A² will be the excess thickness which was originally provided in the blank, that is to say, for example and as mentioned above, this part may project about .02 inch. In the removal of the metal necessary to give the edge A³ of the projecting part A¹ the correct contour the latter may be produced by a pantograph from oversize templates which have been carefully made by hand, an engraving or like machine being used which will take off the unnecessary metal and leave the edge A³ of the projecting part and the surrounding surface A² reasonably smooth.

The sections constituted by the discs A are now assembled on the mandrel D and they will then appear, as shown in Figure 2, as a cylinder the surface of which is interrupted at spaced intervals by a series of annular grooves E the depth of which will vary over different parts of the circumference and will be different as between separate grooves. Each of these grooves, as may be seen in the enlarged view in Figure 6, is formed as to its sides on the one hand by the surface A² on the face of one disc around the projecting part A¹, whose edge A³ forms the bottom of the groove, and on the other hand by the untouched flat face of the next adjacent disc A⁴. The excess metal from the peripheries of the assembled discs is now removed by rough machining followed by hand finishing, as by filing and scraping, which is necessary having regard to the shape which the finished cam is to have at different points along it approximately to the contours of the several projecting parts A¹. The body at this stage is as shown in Figure 3, and on an exaggerated scale the state as between two adjacent discs A and A⁴ is shown in Figure 7 wherein it may be noted that the diameter of the part A¹ is here the same as it is in Figure 6. While the cam body at this stage will approximate in its contour to what is to be the final form of the cam, in its length overall it will be longer than is required for the finished cam.

The next stage is to take all the disc sections off from the mandrel and separate them and from the face of each of them there is then removed the whole of the shaped projecting part A¹ so that the section is left with both its faces flat and parallel to enable them to butt up smoothly against the faces of the next adjacent sections. The sections are now assembled once more and this time permanently on the mandrel and any slight steps between the sections, such as shown in an exaggerated form in Figure 8 between the abutting edges of the adjacent sections, are taken off by grinding or otherwise and the surface of the whole cam is finished. In this state it is shown in Figures 4 and 5 and the appearance of the junction

between the sections is shown in Figure 9 where the diameter at the junction will be seen to be the same as the diameter of the projection part A¹ as seen in Figures 6 and 7. The complete cam will now have the correct overall length.

Such a master cam may be used in the production of a form cam by suitable means as for instance by mounting the master cam and the blank for the form cam on a mandrel which is rotated so as to keep the master cam in contact with a follower while the blank is acted on by a grinding wheel or tool.

In the above description in reference to the drawing it has been assumed that the master cam to be made has a single lobe, but it is to be understood that by employing a similar process it is possible to make such a cam with more than one lobe. In the production from a master cam of a form cam with say two lobes it is preferable to construct the master cam with only one lobe and use this in shaping the form cam with its two lobes. This may be done by first shaping the one part of the blank which is to be the form cam with respect to its one lobe and then the blank and the master cam are relatively turned on their common mandrel through 180° and the shaping of the other part of the blank to form the second lobe is then carried out. In certain cases, however, according to the purpose for which the form cam is to be used it may be desirable to arrange for the operative lobes or parts of the form cam to be set out somewhat radially with respect to the cam axis. The shaping of the form cam may be effected in the following way and as shown in Figures 10 and 11. The master cam A⁵ is identical in form with that shown in Figures 4 and 5 and comprises a lobe portion A⁶ of complex form, which happens to be shown uppermost in Figures 4 and 5, but lowermost in Figure 10, together with a base part of suitable shape which, for example, may be mainly cylindrical since it does not affect the final shape of the part to be copied from the master cam whether this is a work piece or a two-lobed form cam G as shown in Figure 10. The master cam A⁵ and the blank G which is to be the form cam are respectively mounted on parts D¹ and D² of a mandrel which are relatively eccentric the part D² being offset with respect to the part D¹. The form cam G has two lobes G² and G⁴, each identical with the part A⁶ of the master cam, but each situated at a greater distance from the axis about which the cam G is then rotated than the lobe A⁶ is from the axis of the master cam. In the first operation the lobe G² is formed and the form cam at this stage is a complete copy of the master cam A⁵. The next step is to turn the part G on its own eccentric axis through 180° in readiness for removal of the metal indicated at G³. The second lobe G⁴ is then formed leaving only the blending of the metal between the lobes at the points G⁵ and G⁶ to be carried out by hand operation. This two-lobed form cam will then be ready for use when rotated about its true centre. In Figure 11 the outline of the original blank is indicated at G⁷ and that of the parts before final shaping is indicated at G⁸.

What we claim as our invention and desire to secure by Letters Patent is:

1. The herein described method of making a cam comprising the steps of building up a series of separate sections connected together and keyed on a common mandrel in which each section is initially a disc-like member having on one flat face a slightly raised part whose peripheral contour is that to be given to the part of the finished

cam to be constituted by that section, and wherein in all the sections when assembled as a body on the mandrel first having metal removed from their peripheries so as to bring them respectively to the contours of the raised parts on their faces, and then removing these raised parts thereby reducing the thickness of the several sections so that when they are again assembled on the mandrel the cam thus built up will have the desired overall length.

2. The herein described method of making a master cam from which form cams can be reproduced comprising the steps of building a number of separate sections mechanically connected and all keyed on a common mandrel, each section being constituted by a disc-like member of suitable

initial thickness and having this thickness reduced by cutting away the metal on one flat face so as to leave thereon a raised part the peripheral contour of which has the shape which that part of the cam is to have, assembling all of these sections on a mandrel and removing the excess metal down to the shaped edges of the raised parts lying between adjacent sections, separating the sections and removing the raised part on the one flat face of each section leaving both faces flat and parallel, and assembling the sections on the mandrel and finishing off the surface of the whole cam as thus built up.
